(57) **CLAIM**

The ornamental design for a heat transfer packing element, as shown and described.

DESCRIPTION

FIG. 1 shows a front perspective of a heat transfer packing element;

FIG. 2 shows a front elevation view of the heat transfer packing element of FIG. 1;

FIG. 3 shows a rear elevation view of the heat transfer packing element of FIG. 1;

FIG. 4 shows a right elevation view of the heat transfer packing element of FIG. 1;

FIG. 5 shows a left elevation view of the heat transfer packing element of FIG. 1;

FIG. 6 shows a top plan of the heat transfer packing element of FIG. 1; and,

FIG. 7 shows a bottom plan of the heat transfer packing element of FIG. 1.
